UNITED STATES PATENT OFFICE.

HARRIET HILL, OF NEW YORK, N. Y.

SANITARY DRINKING-CUP.

1,056,675.

Specification of Letters Patent.

Patented Mar. 18, 1913.

Application filed June 19, 1912. Serial No. 704,594.

To all whom it may concern:

Be it known that I, HARRIET HILL, a citizen of the United States, residing at 127 East Fiftieth street, New York city, in the county of New York and State of New York, have invented new and useful Improvements in Sanitary Drinking-Cups, of which the following is a specification.

The general object of the invention is to prevent the expansion under the pressure of their contents while in use, of paper drinking cups, and to adapt such cups so to nest in a vending machine that the possibility of their jamming or catching one onto the other when the machine is operated, will be reduced to a minimum. And to this end the invention consists in providing the cup with a lip flange arranged so as to lock the longitudinal plaits of the cup against unfolding under the pressure of water in the cup, and to present a smooth outer surface which will have no tendency to catch onto the mechanism of the vending machine and which will conform more readily to the space between the lips of the user when the cup is in use.

Other objects will appear and be better understood from that embodiment of my invention of which the following is a specification, reference being had to the accompanying drawings forming a part thereof, in which:

Figure 1 is a perspective of the device. Fig. 2 is a detail side elevation of a portion of the upper end of the cup preparatory to forming the flange. Fig. 3 is a detail vertical section showing the flange partly formed. Fig. 4 is a view similar to Fig. 3 showing the next step in forming the flange. Fig. 5 is a view similar to Fig. 4 showing the position of the flange when the cup is ready for use.

The cup *a* is formed of waxed, or waterproofed paper or such other material as is used in the manufacture of devices of this kind and is by preference frusto-conical in contour. The usual strengthening ribs in the form of longitudinal plaits are employed for preventing the collapsing of the cup under ordinary pressure on the exterior thereof.

In carrying out my invention and after the cup is shaped and plaited, the upper

edge portion is folded downwardly and outwardly as indicated at 6, and as clearly shown in Fig. 3. The said upper edge portion is then refolded outwardly and downwardly from a point a trifle below the edge of the first folded portion 6 and as indicated at 7 in Fig. 3. Upon the refolding of the upper edge portion the folded portion 6 will extend upwardly so that the lower edge of the now-formed flange 8 will be blunt as contrasted with the free edge of the folded portion 6, which was prior to its being folded, the raw edge of the paper itself.

With the flange thus far formed as shown in Fig. 4, the cup may be used in the ordinary manner, but the presence of the lower edge of the flange forms a projection which will readily catch onto any uneven portion in the holder of the vending machine and thereby prevent the successful operation of such machine and at the same time the tapered space between the inner face of the flange and adjacent surface of the cup forms a convenient socket for the edge of the cup immediately thereunder while the cups are in a vending machine, so that if the cups be tightly nested one into the other in such machine, there will be great liability of the upper edge of one cup to bind in the socket of the cup which it receives. Therefore, in order to overcome such defect, the flange when positioned as shown in Fig. 4, is subjected to the pressure of a suitable machine which will effect the compression of the said flange onto the outer face of the body of the cup and at the same time flare the flange outwardly. Under the aforesaid pressure, the inner face of the flange will be pressed into contact with the adjacent surface of the cup, and inasmuch as the folded portions which constitute the flange must contract in order to conform to the diameter of the portion of the cups into which they are forced in contact, it will be obvious that upon such contraction the plaits of the flange will telescope one into the other so that the overlapping portions of the plaits of the flange will break joint with those of the body of the cup and the diameter of the lower edge of the flange will be less than the upper edge of the cup. This will have the effect of producing a positive lock for the plaits of the body of the cup and con-

sequently prevent such plaits from unfolding under the pressure produced by the contents of the cup.

What is claimed as new is:

- 5 1. A sanitary drinking cup comprising a cup-shaped body of water-proof material having longitudinal plaits, the plaited upper edge portion of said body being bent upon itself and folded over and pressed onto one face of the body and flared with respect to the portion of the body therebeneath.
- 10 2. A sanitary drinking cup comprising an

upwardly flared cup-shaped body of water-proof material having longitudinal plaits, 15 the plaited upper edge portion of said body being bent upon itself and folded outwardly and pressed onto the outer face of the body and flared with respect to the portion of the body therebeneath.

In testimony whereof I affix my signature in presence of two witnesses.

20 HARRIET HILL.
